UNITED STATES PATENT OFFICE

2,515,572

STORM WINDOW

Theodore L. Smalley, New London, Conn.

Application August 24, 1945, Serial No. 612,437

3 Claims. (Cl. 160—182)

1

This invention relates to a storm window, and more particularly to a readily removable and replaceable storm window.

A primary object of the invention resides in the provision of an improved storm window construction characterized by the absence of protruding or external hardware.

A further object of the invention resides in the provision of such a storm window which will be relatively water-tight, and which is provided with means whereby ventilation may be readily provided when the storm window is in position.

A still further object resides in the provision of such a window which is sturdy and durable in construction, reliable and efficient in operation, and relatively inexpensive and simple to manufacture and assemble.

Other objects will in part be obvious and in part be pointed out as the description of the invention proceeds.

In the drawings wherein there is disclosed the preferred embodiment of this inventive concept:

Figure 1 is a front elevational view of one form of storm window embodying the instant inventive

Figure 2 is a view taken from the opposite side of the window as shown in Figure 1.

Figure 3 is an enlarged sectional view taken substantially along the line 3-3 of Figure 1.

Figure 4 is an enlarged sectional view taken substantially along the line 4-4 of Figure 2.

Figure 5 is a rear elevational view of the frame for the sash, disclosing certain constructional details.

Figure 6 is a front elevational view of a modified form of construction.

Figure 7 is a sectional view taken substantially along the line 7—7 of Figure 2 or Figure 6 as viewed in the direction indicated by the arrows. Figure 8 is a sectional view taken substantially

Figure 8 is a sectional view taken substantially along the line 8-8 of Figure 2 or Figure 6 as viewed in the direction indicated by the arrows, and

Figure 9 is a fragmentary elevational view of a constructive detail.

Similar reference characters refer to similar parts throughout the several views of the drawings.

Having reference now to the drawings and more particularly to Figures 1 and 2, there is generally indicated at 10 a window frame, in which are insertable upper and lower sash members 11 and 12, respectively. The upper sash 11 is preferably comprised of a glass pane, while the lower sash 12 may be alternatively comprised of

1

a second glass pane or a screen insert in accordance with the nature of protection against the weather desired. Both upper and lower inserts 11 and 12 are provided with handles inset in the lower portion frame thereof as indicated at 13 and 14, respectively.

Referring particularly to the lower edge of the frame 10, as indicated at 15 in Figure 8, it will be seen that the same is provided with an exteriorly positioned ridge 16, adapted to be engaged by a groove 17 in the lower portion 18 of the lower sash member 12. Thus it will be seen that in order to remove the insert 12 it is necessary to raise the same to disengage the ridge 16 from the groove 17. As best shown in Figure 3 the side members of the sash 11 are provided with grooves 18, and overlapping projections 19 adapted to overlie the edges or sides of the frame 10, the grooves 18 being adapted to accommodate metal weather stripping strips 20 which extend downwardly substantially half the length of the frame (see Fig. 5), providing a relatively fluid-tight closure for the sides of the device, and holding the same against displacement.

25 In Figure 4 the construction of the sides of the lower sash 12 is disclosed. The frame is rabbeted as at 21, and the sash 12 is provided with an overlapping flange or member 22 adapted to form a relatively fluid-tight seal for the sash with the frame 10.

As best shown in Figure 7 the upper portion of sash 11 is rabbeted as at 27 to engage a corresponding rabbet in the upper portion of frame 10. A resilient spring 28 is secured in the rabbet 25, and serves to bias the upper sash 11 downwardly into abutting relation with the top of the lower sash 12, and hold the same securely in position with the ridge 16 engaging in the groove 17. Side springs 29 are provided, which serve to hold the upper sash 11 in position, when the lower sash is removed.

Obviously, in order to remove the lower sash it is necessary to force the upper sash 11 upwardly against the pressure of spring 28, until the groove 17 may be disengaged from the ridge 16, whereupon the lower sash may be removed. In order to remove the upper sash it is then necessary to slide the same downwardly until the lower extremities of the weather-stripping 20 are passed, thus clearing the channels 18, whereupon the upper sash may be removed outwardly in the same manner as the lower sash.

While single springs 28 and 29 have been indicated, it will be apparent that a plurality of 55 springs 28 may be utilized, or a plurality of springs

29 as may be desirable or necessary. Correspondingly, while leaf springs have been shown, other types of springs may be utilized advantageously.

Figure 6 discloses a modified form of the invention, wherein the inventive concept is applied to windows of the casement type. In this modification a frame 10' is formed at its lower edge in a manner identical to the previously described frame having a ridge 16 as indicated in Figure 8, and at its upper edge with a rabbet 25 as disclosed in Figure 7. In this case weather-stripping 31 is provided only in the upper corners of the frame, and adapted to engage in corresponding grooves in the sides of a one-piece frame 32, provided with a handle 33, the weather-stripping 31 being pivotally mounted on a pin 34 and abutting a friction disk 35, as best shown in Figure 9.

If desired the springs 28 may be supplemented or supplanted by coil springs 36. In this modification it will be readily apparent that the springs will bias the one-piece window frame 32 downwardly to cause the groove in the lower portion of the sash to engage with the ridge on the lower portion of the frame, thus holding the sash securely in place and forming a relatively tight storm window providing a water table at the lower portion thereof.

Obviously, in removing the one-piece sash 32 it is necessary to raise the same against the pressure of the springs in the upper portion of the frame, whereupon the entire device may be tilted outwardly, and removed from the weather-stripping members 31, which it will be noted may swing outwardly when the lower portion of the frame is swung outwardly.

Obviously, in this modification the side springs 29 will be unnecessary.

From the foregoing it will now be seen that there is herein provided an improved window sash accommodating removable inserts, and including, as best shown at 30 in Figure 5, a water table in the lower portion thereof to accommodate any water such as rain which may impact against the window and drain to the lower portion thereof, which accomplishes all the objects of this invention, and others including many advantages of great practical utility and commercial importance.

As many embodiments may be made of this inventive concept, and as many modifications may 50

be made in the embodiment hereinbefore shown and described, it is to be understood that all matter herein is to be interpreted merely as illustrative and not in a limiting sense.

5 I claim:

1. In a storm window, in combination, a rabbeted frame, an upper sash having a rabbet in the upper surface thereof engaged with the frame rabbet, a lower sash having a groove in the lower surface thereof, a ridge on the lower portion of said frame engaging in said groove, said upper sash having a flange adapted for overlapping engagement with the frame, means pressing the upper sash against the lower sash to engage said groove and said ridge, said last-mentioned means comprising a spring insert in the lower side of the upper portion of said frame, side springs abutting the sides of said upper sash, and weather stripping on the sides of said frame engageable in grooves in said upper sash.
2. In a storm window, in combination, a rabbeted frame, a sash having a rabbet in the upper surface thereof engaged with the frame rabbet, and a groove in the lower surface of said sash, a ridge on the lower portion of said frame engaging in said groove, said sash having a flange adapted for overlapping engagement with the frame, and resilient means in said frame pressing said sash downwardly to engage said groove with said ridge.
3. The structure of claim 2 including weather stripping in the corner of said frame, a pin on said frame, said weather stripping being pivotally mounted on said pin, said pin being carried by a friction disk mounted on said frame, said disk and said weather stripping being in abutting relationship.

THEODORE L. SMALLEY.
